[57] CLAIM

The design for a walking sole for attachment to a cleated shoe, substantially as shown and described.

DESCRIPTION

FIG. 1 is a top left and rear perspective view of a walking sole for attachment to a cleated shoe showing my new design;

FIG. 2 is a right side elevational view thereof;

FIG. 3 is a rear elevational view thereof;

FIG. 4 is a front elevational view thereof; and

FIG. 5 is a bottom plan view thereof.
